GAS OPERATED AUTOMATIC FIREARM

Marriner A. Browning, Ogden, Utah, assignor to
 J. M. & M. S. Browning Company, Ogden, Utah,
 a corporation of Utah

Original application February 19, 1934, Serial No.
 711,846. Divided and this application March
 19, 1935, Serial No. 11,793

13 Claims.

(Cl. 89—2)

The invention relates particularly to a gas operated firearm having the piston tube normally connected with the barrel and readily movable rearward to disengage the barrel and to thus permit the barrel to be disconnected from the casing of the gun. In accordance with the invention a buffer is provided which is engageable by the operating slide for cushioning the movement of the latter to normal position. Also in accordance with the invention, the piston tube is arranged to vibrate longitudinally so as to assist in preventing deposits in the cylinder.

This present application constitutes a division of my co-pending application for Automatic firearm, Serial No. 711,846, filed February 19, 1934, which said co-pending application was issued as Patent No. 2,093,705 on September 21, 1937.

In the accompanying drawing I have shown the embodiment of the invention which I now deem preferable, but it will be understood that the drawing is intended for illustrative purposes only and is not to be relied upon as limiting or defining the scope of the invention, the claims forming a part of this specification being relied upon for that purpose.

Of the drawing:

Fig. 1 is a side view of a firearm embodying the invention.

Fig. 2 is an enlarged fragmentary view of the front portion of the firearm, this view being partly a side view and partly a longitudinal sectional view.

Fig. 3 is a view similar to Fig. 2, but showing the parts in different relative positions.

Fig. 4 is a fragmentary perspective view of the rear portion of the barrel.

Fig. 5 is a transverse sectional view taken along the line 5—5 of Fig. 2.

Fig. 6 is an enlarged fragmentary longitudinal sectional view showing the buffer.

Fig. 7 is a plan view showing the connection between the piston rod and operating slide.

Referring to the drawing, 1 represents as an entirety the main breech casing, which is generally rectangular in transverse section. The portion 1^a of the casing near the front is formed to receive the rear end of a barrel 2. Contained within the casing 1 are feeding and firing mechanisms to which the present invention does not particularly relate. The details of these mechanisms are disclosed in my aforesaid application Serial No. 711,846. The casing 1 is closed at the rear by a plate 1, which carries the trigger 8 and control handles 9, 9. The plate 1 with the parts thereon is readily removable.

The barrel 2 is preferably detachably connected with the casing and has a rear cylindrical portion 2^a which fits a cylindrical hole in the portion 1^a of the casing. The rear end of the barrel is provided at 10 with interrupted exter-

nal threads adapted to engage similar internal threads formed in the casing. When the barrel is in the position shown in Figs. 2 and 3 it is firmly held in place by the threads. It can be released by being turned through a quarter turn in the clockwise direction. The barrel is normally held in its locked position by means of a pin 11 held by a spring 12. The rear end of the spring is T-shaped and fits a T-shaped groove 13 in the top of the casing, and a screw 14 normally serves to prevent the spring from moving rearward out of the T-shaped slot. The pin 11 can be withdrawn from the hole in the barrel by means of a suitable tool such as the head of a cartridge and then the barrel can be turned in the clockwise direction to disengage the interrupted threads at 10. This permits the barrel to be drawn out in the forward direction. In order to avoid the necessity for using a tool to replace the barrel, the barrel is provided, as shown in Fig. 4, with a longitudinal groove 15 positioned to receive and provide clearance for the pin 11. The groove 15 has a beveled surface 15^a adjacent its forward end, which surface serves to cam the pin 11 outward when the barrel is moved in the counter-clockwise direction into locking position. As soon as locking position is reached the pin 11 snaps into the hole in the barrel, thus firmly locking it.

The barrel 2 is preferably provided with a series of annular ribs 2^b, 2^c to facilitate cooling. As already explained, the barrel is readily removable, and if excessive heating eventually occurs the gun may be kept in service by removing one barrel and substituting another.

The casing 1 is provided with an integral extension 14 which extends forward underneath the barrel. This extension is hollow and serves to engage and retain a piston tube or cylinder 16. The tube 16 is preferably slidably longitudinally with respect to the casing, and movement in the forward direction is limited by a shoulder 17 on the tube which engages a shoulder 18 on the casing. At its forward end the tube is connected with and supported by the barrel. Preferably the tube is provided at the top thereof with a T-shaped projection 19 which fits a similarly shaped T-slot formed in a band 20 secured to the barrel. With the parts engaged, as shown in Figs. 2 and 5, the tube is held in rigid relationship to the barrel, but by moving the tube rearward it is disengaged from the barrel, as shown in Fig. 3, thus leaving the barrel free to be turned so that it may be disengaged from the casing in the manner already explained.

The tube 16 is normally held in its forward engaged position by means of two links 21 and 22 which are pivotally connected with each other by a pin 23. Preferably the link 21 is U-shaped in cross section so as to partly surround and en-

close the link 22. The link 21 is pivoted to the front end of the portion 14 of the casing by means of a removable pin 24, and the link 22 is pivoted to the tube 16 by means of a pin 25. 5 A spring pressed latch 26 is provided for holding the link 21 in its upper or normal position. It will be observed that with the parts in the positions shown in Fig. 2 the tube 16 is held in its forward position, the link 21 substantially enclosing the link 22. When it is desired to move the tube 16 in the rearward direction the link 21 is disengaged from the latch 26 and the link is moved downward to the position shown in Fig. 3, thus drawing the tube rearward and disengaging the projection 19 from the T-slot in the band 20.

Longitudinally movable along the bottom of the main casing is an operating slide 27, this slide being connected with a piston rod 28 and a piston 29 positioned within the piston tube 16. The forward end of the slide is bifurcated and is considerably wider than the piston rod which is secured to the bifurcated end of the slide by the pin 27^a. The difference in width of these two elements results in the shoulders 27^b on the slide projecting from opposite sides of the piston rod as shown in Fig. 7. Preferably the piston 29 is formed integrally with the rod and consists of one or more annular flanges thereon. A cylinder member 30 is provided in the forward end of the tube 16, being held in place by threads, and the piston 29 accurately fits the said member. A series of registering gas holes connect the bore of the barrel 2 with the interior of the member 30 in order that a portion of the gases of explosion may enter the member and act upon the piston 29 to force it rearward from normal position.

For returning the slide 27 in the forward direction to normal position after it has been moved rearward by the piston and piston rod there is provided a suitable action spring 31 which is preferably located near the rear of the casing 1. It will be understood that the slide 27, during its rearward movement caused by the pressure of the gases and during its return movement caused by the spring, serves to operate the feeding and firing mechanisms of the gun. The reciprocating breech bolt is shown at 49, this being connected 50 with the slide 27 by means of links 50 and 51.

When the slide moves forward under the influence of the spring its movement is limited by a suitable buffer which surrounds the piston rod 28, an enlarged sectional view of this buffer being shown in Fig. 6. The rear portion of the piston tube 16 is formed with a cylindrical recess in which is positioned a split bushing 37 which very loosely fits the opening. The inner surface of the split bushing 37 is tapered and it engages 60 the outer surface of a similarly tapered bushing 38. A removable screw 39 serves to hold the two bushings in place. It will be observed that when the slide 27 moves forward the shoulders 27^b thereon engage the inner bushing 38 which is forced into the outer bushing 37. This outer bushing by reason of the fact that it is split and is resilient offers friction which resists and stops the forward movement of the slide. When the slide again moves rearward the inner bushing 38 70 follows it until limited by the screw 39, the bushing thus being ready to be engaged by the slide upon its next forward movement.

In order to provide a further means for absorbing the energy of the slide at the end of its forward movement, provision may be made for

permitting the entire tube 16 to move from its normal position shown in Figs. 2 and 6 longitudinally through a slight distance. As shown, there is provided a spring pressed plunger 40 carried by the front end portion of the casing 5 which abuts against the shoulder 17 on the tube. In order to permit limited movement of the tube the link 21 is provided with elongated holes for receiving the pivot pin 24. From the foregoing description it will be observed that the energy of 10 the slide is absorbed in part by the two coaxial bushings 37 and 38 and in part by the plunger 40.

Preferably the slide 27 and some of the parts associated therewith, including the piston rod and the piston, are removable from the firearm 15 at the rear thereof. To effect such removal it is necessary to remove the plate 7 with the parts carried thereby.

What I claim is:

1. In an automatic firearm, the combination of 20 a breech casing, breech mechanism in said casing, a barrel, a piston tube connected with the barrel, a gas operated piston and piston rod in the tube, an operating slide connected with the piston rod and movable from and to normal position upon 25 firing of the gun to actuate the breech mechanism, a resilient buffer surrounding the piston rod, and means on the slide engageable with said buffer for cushioning the return movement of the slide to normal position.

2. In an automatic firearm, the combination of 30 a breech casing, breech mechanism in said casing, a barrel, a piston tube connected with the barrel, a gas operated piston and piston rod in the tube, an operating slide connected with the piston rod and movable from and to normal position upon 35 firing of the gun to actuate the breech mechanism, a buffer comprising two concentric frictionally engaging rings surrounding the piston rod, and means on the slide engageable with 40 said buffer for cushioning the return movement of the slide to normal position.

3. In an automatic firearm, the combination of 45 a breech casing, breech mechanism in said casing, a barrel, a piston tube adjacent the barrel, means connecting the tube with the barrel, a gas operated piston and piston rod in the tube movable rearward upon firing, an operating slide connected with the piston rod and movable thereby from and to normal position to actuate the 50 breech mechanism, and a buffer carried by the piston tube for cushioning the return movement of the slide to normal position.

4. In an automatic firearm, the combination of 55 a breech casing, a barrel, a longitudinally movable breech bolt in the casing, a piston tube adjacent the barrel, means normally connecting the tube with the barrel but readily disconnectible to permit endwise movement of the tube, a gas operated piston and piston rod in the tube movable 60 rearward upon firing, a longitudinally movable operating slide rigidly connected with the piston rod to be movable therewith, means connecting the slide with the bolt to enable the former to move the latter, spring means for returning the 65 operating slide and bolt in the forward direction, and a buffer carried by the movable piston tube at the rear end thereof and adapted when the tube is in normal position to be engaged by the operating slide at the end of its forward move- 70 ment.

5. In an automatic firearm, the combination of 75 a breech casing, breech mechanism in said casing, a barrel, a piston tube adjacent the barrel having its forward end connected to the barrel 75

- and a recess in its rearward end, a gas operated piston and piston rod in the tube movable rearward upon firing, an operating slide connected with the piston rod and movable thereby from 5 and to normal position to actuate the breech mechanism, and a buffer surrounding the piston rod and positioned in the recess in the piston tube for cushioning the return movement of the slide to normal position.
- 10 6. In a gas operated firearm, the combination of a breech casing, breech mechanism in said casing, a barrel, gas operated means movable from and to normal position to operate the breech mechanism, a cylinder movably connected with 10 the barrel for movement from and to normal position and having a gas passage therein for conducting gases of explosion to said gas operated means, and means urging said cylinder to its normal position but yieldable to permit movement of the cylinder when engaged by said gas operated means upon movement of the latter to normal position.
- 15 7. In a gas operated firearm, the combination of a breech casing, breech mechanism in said casing, a barrel, gas operated means movable from and to normal position to operate the breech mechanism, a cylinder movably connected with the barrel and casing for movement from and to normal position and having a gas passage therein 20 for conducting gases of explosion to said gas operated means, and means positioned between the casing and cylinder urging said cylinder to its normal position but yieldable to permit movement of the cylinder when engaged by said gas operated means upon movement of the latter to normal position.
- 25 8. The combination in an automatic firearm, of a breech casing, a barrel, a longitudinally movable breech bolt in the casing, a piston tube connected with the barrel and capable of limited longitudinal movement, a gas operated piston and piston rod in the tube movable rearward upon firing, a longitudinally movable operating slide rigidly connected with the piston rod to be movable therewith, the said slide abutting against the piston tube at the end of its forward movement, means connecting the slide with the bolt to enable the former to move the latter, spring means for returning the operating slide and bolt 30 in the forward direction, and a spring means normally holding the piston tube in its rear position and permitting the tube to yield slightly when engaged by the operating slide.
- 35 9. In a gas operated automatic firearm, the combination of a breech casing, breech mechanism in said casing, a barrel, a piston tube connected with the barrel and casing for sliding movement from and to normal position and having a forward facing shoulder near the rear end, 40 gas operated means partially positioned in the tube and movable from and to normal position to operate the breech mechanism and having a shoulder thereon for engagement with the piston tube, and resilient means mounted on the breech casing and engageable by the shoulder on said tube to normally urge the tube rearward but permitting the same to yield slightly in a forward direction when engaged by the shoulder on the gas operated means.
- 45 70 10. In a gas operated automatic firearm, the combination of a breech casing, breech mecha-
- nism in said casing, a barrel, a cylinder connected with the barrel for movement from and to normal position, gas operated means partially positioned within the cylinder and movable from and to normal position to operate the breech mechanism, a buffer for cushioning the movement of the gas operated means to normal position and for transmitting motion from the said gas operated means to the cylinder, and means urging the cylinder to its normal position but yieldable to 5 permit movement of the cylinder by the gas operated means whereby the movement of the gas operated means is further cushioned and the cylinder is caused to vibrate.
- 15 11. In a gas operated automatic firearm, the combination of a casing, breech mechanism in said casing, a barrel, a piston tube having in the rear end thereof a recess and being slidably connected with the barrel for movement from and to normal position, a piston and piston rod reciprocatable in the tube, an operating slide connected with the piston rod for reciprocation therewith from and to normal position to actuate the breech mechanism, a buffer positioned in the recess in the tube for engagement by the slide to 20 cushion its movement to normal position and for transmitting motion from the slide to the tube, and means urging the cylinder to its normal position but yieldable to permit movement of the tube by the slide whereby the movement of the slide 25 is further cushioned and the tube is caused to vibrate.
- 25 12. In a gas operated automatic firearm, the combination of a casing, breech mechanism in said casing, a barrel, a piston tube having a 30 shoulder thereon and being slidably connected with the barrel for movement from and to normal position, a piston and piston rod reciprocatable in the tube, an operating slide connected with the piston rod for reciprocation therewith 40 from and to normal position to actuate the breech mechanism, a buffer for cushioning the movement of the slide to normal position and for transmitting motion from the slide to the tube, and means positioned between the shoulder on 45 the tube and the casing urging the tube to its normal position but yieldable to permit movement of the tube by the slide whereby the movement of the slide is further cushioned and the tube is caused to vibrate.
- 35 13. In a gas operated automatic firearm, the combination of a casing, breech mechanism in said casing, a barrel, a piston tube having at the rear end thereof a recess and a shoulder and being slidably connected with the casing and 50 barrel for movement from and to normal position, a piston and piston rod reciprocatable in the tube, an operating slide connected with the piston rod for reciprocation therewith from and to its normal position to actuate the breech mechanism, a buffer positioned in the recess in said tube for engagement by the slide to cushion its movement to normal position and for transmitting motion from the slide to the tube, and means positioned between the shoulder on the 55 tube and the casing urging the tube to normal position but yieldable to permit movement of the tube by the slide whereby the movement of the slide is further cushioned and the tube is caused 60 to vibrate.

MARRINER A. BROWNING.
